Patented Sept. 14, 1971

221,865

COMBINED HOLDER AND RECHARGER FOR ELECTRIC SHAVERS

Norman D. Poisson, 21 Nicholson St.,
Marblehead, Mass. 01945

Filed Dec. 18, 1969, Ser. No. 20,562

Term of patent 14 years

Int. Cl. D13—02

U.S. Cl. D26—15

Fig. 4.

Fig. 5.

FIG. 1 is a perspective view of a combined holder and recharger for electric shavers showing my new design;

FIG. 2 is a front elevational view thereof;

FIG. 3 is a side elevational view thereof;

FIG. 4 is a top plan view thereof; and

FIG. 5 is a rear elevational view thereof.

The undisclosed side is substantially the same in appearance as the side shown.

I claim:

The ornamental design for a combined holder and recharger for electric shavers, substantially as shown and described.
